W. R. LONG

SHARPENER

Filed May 23, 1924

FIG. 1

FIG. 2

FIG. 3

INVENTOR
William R Long
BY
Arthur C Eckert
ATTORNEY

UNITED STATES PATENT OFFICE.

WILLIAM R. LONG, OF ST. LOUIS, MISSOURI.

SHARPENER.

Application filed May 23, 1924. Serial No. 715,423.

To all whom it may concern:

Be it known that I, WILLIAM R. LONG, a citizen of the United States of America, residing at 2234 Eugenia Street, in the city 5 of St. Louis and State of Missouri, have invented certain new and useful Improvements in Sharpeners, of which the following is a specification.

The object of my device is to make a sharpener to be used particularly for safety razor blades. A further object is to devise a machine for stropping and honing safety razor blades, particularly those of the well known Gillette type. A still further object 15 is to devise a means of easily and simply and manually stropping and honing blades of the type indicated. My device is simple in construction, made of few parts that lend themselves readily to multiple production 20 and can be cheaply produced.

With these and other objects in view, my invention has relation to certain novel features of construction and arrangement of parts as will be hereinafter more fully described, pointed out in the claims and illustrated in the drawing, in which—

Fig. 1 is a perspective view of my device showing the blade holder and a blade in operative position;

Fig. 2 is a cross-section on the line 2—2 of Fig. 1; and

Fig. 3 is a perspective of the blade holder, together with a blade showing the method of detachably securing the blade to the holder.

Numerical 3 designates a block preferably of wood having the channels 4 and 5 formed in it longitudinally in the center, one on each face as best shown in Fig. 2. The upper and lower surfaces are inclined from the outer longitudinal edges to the channels 4 and 5. At the ends of the block 3 are secured the metal straps 6 which entirely cover the ends and which extend along the longitudinal 40 faces and which are secured to the block 3 by screws 7. The width of the straps 6 is equal to the greatest thickness of the block 3. On the inclined upper faces of the block 3 by means of the screws 8 are secured the 45 corrugated metal strips 9 and 10. The corrugations are parallel to the ends of the block 3 and the strips are made of soft steel. The blade holder 11 consists of a metal plate 12 having its ends 13 bent upwardly at right 50 angles to the metal plate 12. Projections 14

are formed on the under surface of the metal plate 12 of such diameter as to permit the blade 15 being laid on to the metal plate 12 with the projections extending through the holes in the blades 15. The metal blade 60 15 is resilient. When it is desired to sharpen the blade 15, it is positioned on the blade holder 11 and then the blade and blade holder laid on the strips 9 and 10 with the projections 14 extending into the channel 4 65 as is best shown in Fig. 1. The ends 13 of the blade holder 11 act as handles or grasping means for the operator. In sharpening the blade 15 the ends 13 are gripped between the thumb and first finger preferably 70 and the blade depressed against the strips 9 and 10. The blade will then assume an arcuated position as best shown in Fig. 2. The sharpening consists in moving the blade holder and blade longitudinally on the block 75 3. It will be seen that the razor edges of the blade will be in contact with the strips 9 and 10. It is the contact of the razor with these strips that sharpens the blade. After this operation has continued for probably a dozen strokes, the blade is reversed and the operation continued.

When it is desirable to only strop the blade or to sharpen it when it is not very dull, the opposite side of the block 3 is used. 85 The projections 14 of the blade holder 11 then extend into the channel 5. In this operation the edges of the blade are rubbed against the surface of the inclined surfaces. If the block 3 is made of a hard wood, such 90 as oak, and the blade moved across it in the manner described a few times, the desired edge will be obtained. The purpose of the straps 6 is to limit the movement of the blade holder 11. The razor blade 15 will 95 strike the inside surface of the strap 6, thereby preventing the razor blade 15 from falling off the end of the block 3.

What I claim and mean to secure by Letters Patent is—

1. A block having a longitudinal channel formed therein and inclined surfaces extending from the longitudinal sides of the block to the channel, metal strips secured to the inclined surfaces of said block, said strips 105 corrugated with the corrugations parallel to the ends of the block.

2. A block having a longitudinal channel on its upper surface and a similar channel centrally located on the lower surface, and 110

having inclined surfaces extending from the longitudinal sides of said block to said channels.

3. A block having a longitudinal channel on its upper surface and a similar channel centrally located on the lower surface, and having inclined surfaces extending from the longitudinal sides of said block to said channels, metal strips secured to the inclined

10 surfaces of one face of said block.

4. A device of the character described comprising a block having longitudinal cen-

trally located channels formed on the upper and lower surfaces, a metal corrugated strip formed on the inclined surfaces of one of the faces of said block, a blade holder having projections extending therefrom so that the projections may be extended into the channels of said block permitting the blade holder being moved longitudinally in the channel 20 of said block.

In testimony whereof I affix my signature:

WILLIAM R. LONG.
